STEP-BY-STEP TYPE PENCIL

Anthony P. Lynn, Elmhurst, Ill.

Application April 20, 1945, Serial No. 589,810

10 Claims. (Cl. 120—17)

1

In mechanical pencils much thought has been devoted to the purpose of producing such pencils economically, but with reliable operation. One of the most popular types has been the repeater type pencil, in which the lead is fed by pressing on the top of the pencil. This may also be called a step-by-step type of mechanical pencil.

According to the present invention a thoroughly reliable repeater type of pencil is provided in which manufacturing costs are extremely low, lower than the manufacturing costs of such pencils known heretofore.

In addition, a new and simplified form of an adjustable pencil eraser is provided, and also a new, simplified and rugged form of clip.

Additional objects and advantages of the invention will become apparent from the following description and from the drawings, in which:

Figure 1 is a longitudinal sectional view of the form of pencil chosen for illustration of this invention;

Fig. 2 is a longitudinal sectional view of a somewhat larger scale showing the eraser in a raised position;

Fig. 3 is a fragmentary longitudinal sectional view on a larger scale than Fig. 1;

Fig. 4 is a transverse sectional view taken on line 4—4 of Fig. 3;

Fig. 5 is a fragmentary detailed view of the bayonet clamp for the feed tube;

Fig. 6 is an enlarged face view of the feed tube;

Fig. 7 is an exploded view of the clip and the securing means therefor; and

Fig. 8 is a transverse sectional view taken approximately on line 8—8 of Fig. 1.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

In the form of the invention chosen for illustration, the pencil includes a barrel 11 which may desirably be formed of a plastic. It includes a large bore 12 communicating at its lower end with a smaller bore 13, a shoulder 14 being formed between the two bores. The bores may be formed by molding or drilling.

Within the barrel 11, a magazine and feeding mechanism is inserted from the open upper end

5 of the barrel. This mechanism includes a magazine 16, a feed tube 17, a clutch housing tube or clutch case 18, and a clutch ring 19. The inward movement of clutch case 18 into barrel 11 is limited by engagement of bead 20 with shoulder 14. The magazine 16 or some member such as eraser 21 carried thereby, projects from the upper end of the tube and is normally held in this position by spring 22 which is compressed between the magazine and the clutch housing case 18. When the user presses the eraser 21 downwardly, this moves the magazine 16, the feed tube 17, and the clutch ring 19 downwardly until the clutch 19 strikes shoulder 23 in the clutch case. Further pressure on the eraser 21 presses the feed tube 17 further downwardly until clutch lugs 24 thereon are entirely free of the clutch ring 19 so that the jaws 25 forming the end of the feed tube 17 can expand toward the position shown in Fig. 6. This will permit a lead 26 to drop until it engages the tip 27 of the clutch case. If a lead is already in place in the tip 27 the downward movement of the parts will move the lead downwardly through the tip 27 into writing position prior to release of the lead by the expanding jaws 25 at which time the tip 27 would hold the lead in this position. The tip 27 is preferably split so as to grip the lead resiliently.

20 Upon release of the operating pressure from the eraser 21, the spring 22 raises the magazine 16, the feed tube 17, and the clutch 19. The clutch 19 rides idly above the lugs 24 until the clutch engages a shoulder or constriction 28 in the clutch case 18 at which time the continuing pressure of spring 22 would cause the lugs 24 to be drawn partly into the clutch 19 to clamp the jaws 25 against the lead 26; thus firmly holding the lead for writing purposes and for feeding on the next operation of the mechanism.

25 Upon the next operation, all of the movable parts, including the lead 26, move in unison until the clutch 19 again strikes the shoulder 23. Thus the lead would be further advanced by the distance that the clutch 19 reciprocates.

30 When the feed tube 17 is empty, movement of the parts is limited by the engagement between lugs 31 and slotted washer 32 which may be secured at the upper end of the clutch case 18 in the manner seen in Fig. 3. The slots 33 in washer 32 are preferably slightly displaced from 180° displacement so that the lugs 31 can only slip past them in one position. The lugs, of course, are correspondingly displaced from 180° separation. The purpose of this is so that it will be extremely rare for the parts to be in such position that they will come apart accidentally.

by passage of the lugs 31 through the slots 33. Of course this would only happen in the rare instances when the parts are in just the right relative position and when there is no lead in the feed tube 17.

If this is found to happen objectionably often, the slots 33 may be slightly undersize so that the lugs 31 can only be drawn therethrough with considerable force. Complete separability of the parts is desirable, however, for the purposes of facilitating repair. The feed tube is secured to the magazine 16 in any suitable manner but is preferably readily removable. At this end the feed tube 17 may be provided with lugs 36 which engage bayonet clamp members 37 formed on a depending portion 38 forming an extension of magazine 16; the bayonet members 37 are preferably provided with humps 39 which tightly engage the lugs 36 as the lugs are turned past them so that once they have been turned past the humps, they will not be accidentally turned to the releasing position. In other words, the bayonet clamp members must be sprung to get the lugs 36 past the humps 39.

Feed tube

One of the important features of the invention is the simplicity of the feed tube 17 and the ease with which it may be manufactured.

First a simple straight length of tubing is cut; next the three sets of lugs 24, 31 and 36 are formed thereon simultaneously in a press which merely pinches this metal from the body of the tube by external pressing. Next a simple swaging operation reduces the end of the tube against a threaded mandrel of smaller diameter than the inside of the tube which places threads therein, after which the mandrel is rotated to release it from the threads. The swaging member may be in the form of a collet moving longitudinally of the tube and very slightly reducing the diameter at the end of the tube as seen at 42. Next the lower end of the tube is slit with a fine saw which makes a cut about .010 of an inch to form the slots 41 between jaws 25.

It will usually be desirable to spread the jaws 25 apart so that they will naturally assume the position shown in Fig. 6 in order to be sure that the threads on the inside of the jaw will give adequate clearance for a lead passing therethrough when the jaws are not clamped against the lead by the clutch ring 19.

The feed tube 17 is now reamed from the upper end to remove any burrs or objectionable constrictions. With these simple operations the feed tube is ready for use.

The lugs 24 should be tapered, lower at their upper ends so as to provide a progressive clamping action as they are drawn into the clutch. If their upper edges are not flush with the walls of the tube, they should be smoothly rounded toward it so they will not catch on the lower edge of the clutch 19. This permits cutting the clutch square at its lower end, although, of course, it could be internally bevelled if preferred. Preferably the upper end of the clutch is bevelled internally, as seen at Fig. 3, so as to facilitate the insertion of the feed tube 17 therethrough.

Clutch case

The clutch case 18 can also be formed economically. It could be drawn from sheet stock or swaged from a tube. In either case a stepped mandrel would be used to produce the shoulder 23 and the converging tip portion. If sheet stock has been used, the next step would be to punch

or drill a hole at the tip. Next a slot 44 is cut to provide a resilient gripping of the lead. Next the upper end is shaped to provide annular bead 20 and to receive the washer 32. Thereafter the clutch 19 is inserted and the annular internal bead 28 is formed to limit movement of the clutch. Then the washer 32 is inserted and the flange of tube or case 18 rolled over to maintain the washer in place.

10

Magazine

The magazine 16 may also be formed by a simple process. A tube of the full diameter of this magazine would first be swaged at one end or otherwise reduced to provide the sloping portion 46 and the extension 38 of smaller diameter. The bayonet slots would be cut preferably by punching, and a bead 46 (Fig. 1) would be formed to limit the movement of the eraser assembly into the magazine. The sloping portion 46 is inclined approximately as shown so that the leads 26 will have a slight tendency to move toward the tube 17, but not enough to cause jamming. In order that no lead will catch on the upper end of tube 17, it is preferred that a cupped washer 45 be positioned as shown, having a press fit with the walls of the magazine 16 so as to stay in place.

25

Eraser assembly

30

The eraser assembly may include, in addition to the eraser 21, a stirrup 47 by which it is directly carried and a cup 48 which receives the stirrup 47 and holds it with resilient friction.

35

It is very desirable that some way be provided to adjust the eraser 21 upwardly as it wears down. According to the present invention this is accomplished by the very simple expedient by providing parallel saw cuts 49 in the wall of cup 48, thus forming deformable bands 51. There may be two sets of these bands on opposite sides of the cup, or there may be more than two sets equally spaced around the cup. One set would do, but more than one is preferred.

40

When the eraser has been worn down it may be pushed up in the cup 48 and the bands 51 immediately below its raised position are pressed in with a fingernail, to support the eraser in its new position. A hole 52 is preferably provided in the bottom of cup 48 so that if the eraser has been worn down too much to be gripped, it may easily be pushed out from the bottom.

45

Clip

50

Clips made with the simple shape illustrated in Figs. 1 and 8 have not been very satisfactory heretofore, because the split collars 56 would yield too easily and allow the clip arm 57 to be pulled laterally from the pencil. According to the present invention this is overcome by providing a ferrule 58 which surrounds the collars 56 and reinforces them. The ferrule 58 is preferably provided with annular internal recesses 59 adapted to receive the collars 56. Upon application the clip is first placed within the ferrule 58 with the collars in place within the recesses 59. This assembly is then slipped over the end of the barrel 11. The split collars 56 are shaped to grip the barrel 11 so as to hold the parts in place.

55

The ferrule 58 prevents their being sprung by a lateral force which they are not well adapted to resist. To apply the assembly to the barrel 11, the collars 56 may be spread temporarily within the recesses 59 by a suitable spreading tool or mandrel which will hold each collar spread until

75

it has passed over the end of the barrel 11. If the barrel is sufficiently rounded or tapered at its end, this will not be necessary.

The parts may be made of any suitable materials. At present brass is preferred for most of the metal parts, including magazine 16, feed tube 17, clutch case 18 and clutch ring 19 because of ease of reshaping, and resistance to excessive corrosion.

From the foregoing it is seen that a pencil is provided which can be manufactured very economically and which is, nevertheless, thoroughly reliable when properly handled. In case improper handling causes a pencil to get out of order, it may easily be taken apart for repairs or replacements.

I claim:

1. A pencil including a magazine, a feed tube secured to and communicating with the magazine, a clutch case into which the feed tube extends, a clutch ring slideable within the clutch case and through which the feed tube extends, said feed tube being slotted at its lower end to form jaws and having a plurality of sets of lugs pressed therefrom, one set cooperating with the clutch ring to progressively clamp the jaws of the feed tube against a lead, another set cooperating with the clutch case to limit the movement of the feed tube from the case and another cooperating with securing means on the magazine for securing the feed tube to the magazine.

2. A pencil including a magazine, a feed tube secured to and communicating with the magazine, a clutch case into which the feed tube extends, a clutch ring slideable within the clutch case and through which the feed tube extends, said feed tube being slotted at its lower end to form jaws and having a plurality of sets of lugs pressed therefrom, one set cooperating with the clutch ring to progressively clamp the jaws of the feed tube against a lead, and another cooperating with securing means on the magazine for securing the feed tube to the magazine.

3. A pencil including a barrel having a large bore, a smaller bore projecting downwardly therefrom, a clutch case in the small bore and extending from the barrel to form the tip of the pencil and having an enlarged portion limiting the movement thereof into the small bore, a clutch ring slideably positioned in the clutch case, a feed tube extending into the clutch case and into the clutch ring, a magazine carried by the feed tube and communicating therewith and a spring compressed between the magazine and the clutch case, said pencil including means restraining the feed tube within the clutch case to maintain said spring compressed.

4. A clutch assembly for step-by-step type pencils including a clutch case in the form of a tube having a bore therein shaped with portions of larger and smaller diameter and an internally extending bead formed in the tube at a point spaced along the larger bore from the smaller, a clutch ring confined within a larger bore between the smaller and the bead, being longitudinally movable between them, an externally projecting bead forming a shoulder for limiting the movement of the clutch case within a pencil barrel and a slotted retaining member associated with said last named bead and rigid with the clutch case to receive and restrain a feed tube extending into the clutch case.

5. A clutch assembly for step-by-step type pencils including a clutch case in the form of a tube having a stepped bore therein to form

a shoulder between the larger and smaller portions of the bore and an internally extending bead formed in the tube at a point spaced along the larger bore from the shoulder, a clutch ring confined within a larger bore between the shoulder and the bead, being longitudinally movable between them, an externally projecting bead forming a shoulder for limiting the movement of the clutch case within a pencil barrel and a retaining member associated with said last named bead and rigid with the clutch case to receive and restrain a feed tube extending into the clutch case.

6. The method of forming a feed and clutch tube for step-by-step pencils which includes the

steps of pressing the outside walls of a tube to pinch at least one set of externally projecting lugs on the tube, swaging the end of the tube against a roughened mandrel of smaller diameter than the inside of the tube, and slotting the tube from the swaged end to provide a plurality of jaws each including an internally roughened grip portion and a lug.

7. A clutch assembly for step-by-step type pencils including a clutch case in the form of a tube having a bore therein shaped with portions of larger and smaller diameter and an internally extending bead formed in the tube at a point spaced along the larger portion from the smaller, a clutch ring confined within the larger portion between the smaller portion and the bead, being longitudinally movable between them, an externally projecting bead forming a shoulder for limiting the movement of the clutch case within a pencil barrel and a slotted retaining member associated with said last-named bead and rigid with the clutch case to receive and restrain a feed tube extending into the clutch case.

8. A clutch assembly for step-by-step type pencils including a clutch case having spaced constrictions, a clutch ring confined within the clutch case and movable longitudinally between said constrictions therein, a slotted retaining member rigidly associated with the clutch case, a feed tube extending through the slotted retaining member and into the clutch ring, said feed tube having lug means thereon engaging the slotted retaining member for restraining the feed tube from movement out of the clutch case except upon a special relationship of the lug means to the slot of the retaining member angularly about a common axis.

9. A feed and clutch tube for step-by-step type pencils comprising a length of tube slotted at one end to form jaws, and a plurality of sets of lugs pressed out from said tube including one set disposed near the ends of said jaws to cooperate with a clutch ring for clamping the jaws against a lead therebetween, another set disposed adjacent the other end of the tube to secure the tubing to a lead magazine, and an intermediate set for limiting the movement of the feed tube within a clutch case.

10. A feed and clutch tube for step-by-step type pencils comprising a length of tube slotted at one end to form jaws, and a plurality of sets of lugs pressed out from said tube including one set disposed near the ends of said jaws to cooperate with a clutch ring for clamping the jaws against a lead therebetween, and another set disposed adjacent the other end of the tube to secure the tubing to a lead magazine.
